UNITED STATES PATENT OFFICE

2,657,624

WINDOW VENTILATOR

Arthur Edward Wittenberg, Los Angeles, Calif.

Application October 1, 1948, Serial No. 52,225

5 Claims. (Cl. 98—99.2)

1

This invention relates to window ventilators and more particularly to a window ventilator adapted for universal use upon double-hung windows or the like, the construction being characterized as much as possible by draftless design for controlled ventilation.

It is intended by the instant construction to provide a window ventilator directed to the removal of air-borne filth such as dust, soot, cinders and the like, as well as smoke and rain, and which is substantially draft-free.

It is also intended to provide a window ventilator of the desired character described which is usable with equal facility upon trains, street cars, buses and subways, or homes and offices, and otherwise universally where double-hung windows are found.

Among the objects of this invention is the provision of a window ventilator of improved collapsible construction.

It is another object of this invention to provide a window ventilator whose panels are composed of transparent or other light-transmitting material, preferably such as will also transmit ultraviolet rays.

Another object of the invention is the provision of removable and replaceable panels comprising the framework of the ventilator.

Another further object of the invention is the provision of an improved ventilator construction adapted to be optionally formed with a wood or metal framework, or totally or partially moulded from plastic in complete panels and sections.

Another object of the invention is to provide a novel folding relationship of the parts, a novel and improved hinge construction, and an improved arrangement of the parts with relationship to each other and to a window and frame to which it is to be applied.

Another object of the invention is the provision of a window ventilator of sturdy construction and neat and pleasing design, the amount of air passing through the same being subject to control by raising and lowering of the window without disturbing the ventilator.

Another object of the invention is the provision of novel means for securing the same to windows of varying widths.

A further object includes the provision of a window ventilator of the desired character capable of ready and economical mass production, all of whose parts are interchangeable, and which provides improvements in air sifting and circulation principles as well as in details of design.

With these and other objects in view, the in-

2

vention consists in the construction, arrangement and combination of the various parts of the device whereby the objects contemplated are attained, as hereinafter set forth, pointed out in the appended claims, and illustrated in the accompanying drawings.

In the drawings:

Figure 1 is a perspective view of a window ventilator embodying this invention as applied to a double-hung window.

Figure 2 is a sectional view taken as on a line 2—2 of Figure 1.

Figure 3 is a fragmental sectional view taken as on a line 3—3 of Figure 2.

Figure 4 is a sectional view taken as on a line 4—4 of Figure 1.

Figure 5 is a side view in elevation of a folded condition of the ventilator.

Figure 6 is a sectional view of a modified hinge construction as for a frame of sheet metal or the like.

Referring more particularly to the drawings, a ventilator generally designated by the numeral 10 is illustrated by way of example, and not of limitation, within a window frame 11 mounting a double-hung window 12.

The ventilator generally comprises a top panel 13, a front panel 14, a bottom panel 15, a back panel 16, and corresponding side or end panels 17. The top panel may be secured to the front panel by a hinge generally designated at 18 preferably extending from side to side of the ventilator and comprising a partially cylindrical tongue or the like 18' and a corresponding partially cylindrical groove 19. The top panel, for example, may be undercut as at 20 to permit downward folding of the same as will be seen.

The rear panel may be pivotally secured as by a hinge 21 to the bottom 15 and may be similarly undercut as at 22 to permit the inward and forward folding of the back panel 16. Again, the side panels 17 may be hinged as at 24, a male portion 25 of such hinge being preferably formed integrally with each panel, especially if the latter be made of plastic or the like material. Said male member is preferably offset as at 26 from the plane of either side panel in order that these may be free to swing inwardly in the folded position of the ventilator. To accommodate a rear-most edge 28 of the side panels in their unfolded position, the rear panel may be formed with vertical channels 27.

The front panel may be provided with an opening 30 and groove 31 formed therearound for the slidable insertion through slot 32 of a

glass or plastic pane 33 from one end of the ventilator.

The top panel may be channeled as at 34 for the securing of a frame 35 holding a screen 36 made of plastic, wire or the like.

Similarly, the rear panel may be formed with a frame 37 carrying a screen 38 and normally held within a corresponding recess 39 in the back panel.

Lateral extensions 40 provided for either end of the back panel may be telescoped or otherwise slidably associated with the same as by means of longitudinal channels 41 formed in the back panel. Said extensions may be of any desired thickness but preferably sufficient to extend back to the rearmost edge 42 of the back panel and include narrow flanges or feather-like edges 43.

In use, this ventilator may be positioned as upon a window sill 45 with the rearmost edge 42 in alignment with the inner edge of the window 12 so that the window may have slidable engagement with the back side and hence be closable to any desired extent. As commonly used the window is opened, in a manner illustrated in Figure 1, to a position corresponding with the height of the ventilator screen 38. The lateral extensions 40 are positioned within the space between the window and its conventional guides 46.

In order to fold the device as for transport, the lateral extensions 40 may be telescoped inwardly 30 flush with the side panels 17. The rear panel may then be folded forwardly and the top panel downwardly.

A downwardly projecting flange 47 on the top panel may extend beyond the back panel in order to hold the same forwardly and against the rearmost edge 28 of the side panels, thereby stabilizing and reinforcing the apparatus in its unfolded position. It will be noted that in order to unfold the apparatus, the back panel must be swung rearwardly to a sufficient extent to permit the side panels to be brought within the grooves 27. Accordingly, the flange 47 will have to be cleared by the rear panel. For such purpose, the hinges 18 and 21 may have chamfered edges 48 and 49 45 providing sufficient play for forward and rearward movement. The side panels are nested at top, as indicated at 49', in a channel and against a shoulder 50 of the bottom 15.

Thus, all parts of the ventilator are protected 50 against leaks and drafts so that in the event the same is placed in close proximity to a person, no annoyance will be encountered.

In view of the downward and rearward slant of the upper panel, the front panel is higher than any other part of the ventilator, permitting a greater amount of deflection and requiring the entrant air to pass upwardly and rearwardly through the screen 36 at an angle. Although the entering air is not thereby impeded, suspended particles will tend to be separated. Moreover, the shape of the internal structure is such that some turbulence and whirling of the air is created, causing further separation and increasing efficiency in the elimination of foreign matter.

It has been found that a proper proportioning of the structure illustrated is obtained when the front panel rises approximately three inches above the rear panel.

With the instant construction, approximately ten percent of dust and soot is separated at the first screen. After passing through the uppermost screen 36, all but approximately ten percent of dust and smoke is eliminated. Substantially 75

all rain, cinders and other such matter is stopped at the second screen.

In the event sheet metal is used for the general frame, a scroll-type hinge, seen in cross-section in Figure 5, is preferred in lieu of the hinges of Figures 1 through 4. Thus, the top 51 may be formed with a scroll-type edge 52 to interfit with a similar edge 53 on the back front panel 54, for example.

This invention features the provision of a ventilator which can be adapted to windows of varying width, which may be folded for transport, which is constructed to prevent leakage of air, and whose slanted portions cause a desired turbulence and change of air direction necessary to achieve an optimum air-cleansing and ventilating effect with controlled, draft-free ventilation. The invention also features the induction or control of ventilation either where the air is normally in motion, as in buses, or in otherwise "close" or foul areas, provides insurance against draft, and fosters healthful ventilation without exclusion of light rays including ultra-violet rays.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what I claim as new and desire to secure by Letters Patent is:

1. A ventilator for double-hung windows comprising an essentially box-like frame defining top, front, end, bottom and back panels, wherein the back and top panels respectively have apertures to admit the free passage of air, the top panel having a longitudinal continuous hinged connection to the front panel, the back panel having a longitudinal continuous hinged connection to the bottom panel and the end panels respectively having longitudinal continuous hinged connections to the front panel, said hinged connections being swingable inwardly whereby the top panel may be folded downwardly, the end panels inwardly and the rear panel forwardly to render the ventilator compact, said hinged connections comprising interfitting cylinder-like longitudinal channels and tongues formed in said panels for air-tight relative foldable movement of said panels, slideable lateral extensions at either side of the ventilator having telescoping connections with the back panel for engagement in window channels normally provided at either side of a double-hung window, vertical grooves formed in the back panel for reception of the rearmost edges of the side panels, and a downwardly directed lip on the top panel engageable with the back panel in the unfolded position of the ventilator for retaining the rearmost edges of the side panels firmly within said vertical grooves.

2. A ventilator as characterized in claim 1 in which said lateral extensions include a thin vertical outer edge adapted to be slipped between the double-hung window and its channels in a manner to permit the window to be opened to any desired extent without hindrance by said thin outer edges.

3. A portable unitary ventilator for double-hung windows comprising an essentially box-like frame defining top, front, end, bottom and back panels, the top panel having a longitudinal con-

tinuous hinged connection to the front panel, the back panel having a longitudinal continuous hinged connection to the bottom panel and the end panels respectively having longitudinal continuous hinged connections to the front panel, 5 said hinged connections being swingable inwardly, the panel at one side of the hinged connection in each case being formed with a continuous tongue and the panel at the other side of the hinged connection with a continuous groove 10 adapted to receive the tongue, said hinged connections being foldable inwardly whereby the top panel may be folded downwardly, the end panels inwardly and the back panel forwardly to render the ventilator compact, the top and back 15 panels comprising screens.

4. A ventilator as characterized in claim 3, in which the front panel is higher than the back panel and the side panels have an upper edge slanting upwardly between the top of the back 20 panel and the top of the front panel.

5. A ventilator for double-hung windows comprising an essentially box-like frame defining top, front, end, bottom and back panels, the top, back and end panels being foldable relative to 25 the front and bottom panels, and formed with

continuous hinges in common therewith whereby the top panel may be folded downwardly, the end panels inwardly and the rear panel forwardly to render the ventilator compact, said hinges comprising interfitting cylinder-like longitudinal channels and tongues formed in said panels for airtight relative foldable movement of said panels, said longitudinal interfitting channels being scroll-like.

ARTHUR EDWARD WITTENBERG.
